CLAIM

We claim the ornamental design for a formable stand system, as shown and described.

DESCRIPTION

FIG. 1 is a top perspective view of a first embodiment of a formable stand system of the present invention;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a top perspective view of a second embodiment of a formable stand system of the present invention;

FIG. 9 is a front view thereof;

FIG. 10 is a rear view thereof;

FIG. 11 is a left side view thereof;

FIG. 12 is a right side view thereof;

FIG. 13 is a top view thereof; and,

FIG. 14 is a bottom view thereof.

The ornamental design which is claimed is shown in solid lines in the drawings.

The broken lines shown in the drawings form no part of the claimed design.
